CONTAINERS

Edward W. Moon 3rd, Pomfret, Conn., assignor to American Optical Company, Southbridge, Mass., a voluntary association of Massachusetts

Application August 21, 1953, Serial No. 375,767

6 Claims. (Cl. 150—5)

This invention relates to improvements in containers and has particular reference to the provision of a novel light-weight and durable container comprising a main body portion having a cover formed as an integrally attached part thereof.

Small containers such as are used for carrying medical supplies or other materials are sometimes carried in the pockets or elsewhere on the persons of individuals. It is essential to provide such containers with covers which must effectively seal the openings into the interiors of the containers and also which have means whereby the covers are constantly in attached relation to the container bodies to prevent loss thereof which would render the containers ineffective for further use. Since such containers may be carried in an individual's clothing pockets it is also advisable to make them light in weight and resistant to crushing and to provide them with no protrusions such as clips, handles, hinges, or the like which might catch on the clothing as they are being removed from the pockets. The resultant delay in such instances may be very detrimental, depending upon the prevailing circumstances and the specific intended use of the containers.

Therefore it is a primary object of this invention to provide a lightweight and durable container having a tightly sealing cover integrally attached thereto, with the said attaching means being so formed as to function as an aid in loosening the cover from its intimately closed relation with the main body portion and with the resultant container having no undesirable protrusions.

Another object is to provide a container of the above character wherein the cover is attached to the main body portion of the container by an integral band or strap.

Another object is the provision of a container of the above character wherein the connecting strap for the container cover overlies the cover and, while affording means for aiding in removing the cover, it is adapted to assume a relatively close relation with said cover when in closed position whereby it will not be an undesirable protrusion such as might catch onto clothing as the container is removed from a pocket or the like.

A further object is to provide a container formed of molded plastic material having a plurality of compartments therein and having a cover portion attached thereto by an integral molded strap portion whereby the cover forms a single unitary integral and relatively undetachable portion thereof.

A still further object is to provide a container of the above character which is leak proof, water resistant and reusable, and which may be molded in such a manner that printed instructions or other lettering may be molded directly into the material of the container.

Other objects and advantages of this invention will become apparent from the following description taken in connection with the accompanying drawings wherein:

Fig. 1 is a front perspective view of a container embodying a preferred form of the invention;

Fig. 2 is an enlarged vertical longitudinal sectional

view taken substantially on line 2—2 of Fig. 1 looking in the direction of the arrows;

Fig. 3 is a horizontal sectional view taken substantially on line 3—3 of Fig. 2 looking in the direction of the arrows; and

Fig. 4 is a vertical transverse sectional view taken substantially on line 4—4 of Fig. 2 looking in the direction of the arrows and showing the cover in closed and open relation with the main body portion of the container.

Referring more particularly to the drawings wherein like characters of reference designate like parts throughout the several views, the container illustrated comprises a main body portion 10 having an open mouth portion on one side thereof and a cover 11 which is connected to the main body portion 10 adjacent said mouth portion by a band or strap 12. The main body portion 10, cover 11 and strap 12 are formed as a one-piece unitary relatively undetachable structure molded of a suitable plastic material such as polyethylene, vinyl or nylon. The preferred plastic material should be water resistant, easily molded, resistant to relatively high temperatures, and preferably should also possess some degree of resistance to acids. The structure also may be molded by any conventional molding process, which process does not constitute part of this invention.

The main body portion 10 is preferably formed to a relatively flat rectangular shape and is provided with a plurality of vertical longitudinally arranged compartments 13 of similar and different sizes and shapes separated by integral molded walls 14. The ends and bottom of the main body portion 10 are rounded and the side walls are smooth and unbroken. Thus the device can be easily slid into and out of a pocket or other receptacle therefor and no protrusions, cavities or relatively sharp edges will exist to the detriment of easy removal of the container from its receptacle. The walls or separators 14 between the compartments 13 also serve as reinforcement means to prevent damage to the container and its contents when the container is subjected to crushing forces.

At the extreme upper end of the main body portion 10 adjacent the open mouth portion thereof is integrally attached one end of the band or strap 12 which is integrally connected at its other end to one side of the cover 11. The strap 12 is flexible so that the cover may be easily removed or attached to the main body portion 10. The cover 11 is shaped to have a relatively flat exposed portion 15 having extending from one surface 16 thereof a continuous flange 17 which is shaped to intimately fit within the upper end of the main body portion 10 as shown in Figs. 2 and 4. The flange 17 is spaced slightly inwardly of the peripheral edge of the flat portion 15 and thus the surface 16 is provided with a portion 18 lying outwardly of the flange 17 which overlies the end of the main body portion 10.

The space inwardly of the flange 17 forms a compartment 19 in itself while a still further compartment 20 may be provided if desired, as shown in Figs. 2 and 4, by a small annular flange 21. This compartment 20 may, in the assembled structure, be aligned with one of the compartments 13 if desired to assist in the support of a selected article to be located therein.

The outer side surface of the flange 17 is provided with a continuous circumferential bead 24 which is adapted to be positioned in a closely interfitting groove or channel 25 provided therefor in the inner surfaces of the main body portion 10. Thus, the cover 11 is made to more intimately interfit with the main body portion 10 whereby it will remain in closed relation therewith even during possible impact with said main body portion 10 during use. Such construction also renders the device even more water-tight.

3

The flange 17 is also preferably provided with a bevel 22 on its outer peripheral edge whereby the flange 17 may be more easily inserted in the open end of the main body portion 10 to secure the cover 11 in closed relation therewith.

One end of the strap 12 is attached to an edge 23 of the flat portion 15 of the cover 11 and, when positioning the cover 11 in closed relation with the main body portion 10, the edge 23 is preferably located at the side of the main body portion opposite to the side to which the opposed end of the strap 12 is attached. Thus, the strap 12 will overlie the outer surface of the flat portion 15 of the cover 11 as shown in Figs. 1 and 4 and will provide means which may be gripped to aid in removing the cover 11 from the main body portion.

While it is desirable that the strap 12 be spaced a sufficient distance from the outer surface of the cover 11, to permit gripping, its length is controlled so that it will not be spaced from the cover to such an extent that it forms an undesirable protrusion.

Since the flange 17 on the cover 11 is adapted to fit very intimately with the main body portion 10, the extreme upper ends of the side walls of the main body portion 10 are each provided with a small inwardly disposed bevel 26 which the ends of the cover 11 overlie, as shown at 18, to produce a ledge for receiving a prying instrument or the finger nail of an individual whereby the cover may be more easily removed.

While the container embodying the present invention has been shown and described as embodying a specific exterior shape and as having compartments therein, it is to be understood that the container may take other shapes if desired. Also it is apparent that if desired instructions or other reading matter may easily be molded into the exterior surfaces of the container without forming undesirable protrusions.

From the foregoing description it will be apparent that an improved container has been provided in accordance with the objects of this invention.

While the novel features of the invention have been shown and described and are pointed out in the annexed claims, it is to be understood that various omissions, substitutions and changes in the construction and arrangement of parts shown and described may be made by those skilled in the art without departing from the spirit of the invention. Therefore it is to be understood that all matter shown or described is to be interpreted as illustrative and not in a limiting sense.

I claim:

1. A molded plastic container comprising a hollow main body portion having an open mouth portion at one end, a cover having a flange-like portion shaped to intimately interfit with and seal said open mouth portion and having a peripheral edge portion adapted to overlie the peripheral edge of said main body portion encircling said open mouth portion, a strap portion having one end said open mouth portion, a strap portion having one end formed integral with the peripheral edge of the main body portion encircling said open mouth portion and having its opposed end formed integral with an edge portion of said cover whereby said cover is relatively undetachable from said main body portion, said cover being adapted to be positioned in said open mouth portion with the edge portion thereof having the strap affixed thereto being at a location remote from the terminus of the strap with said body portion whereby the cover lies beneath the strap and said strap having a length such that it will overlie the exposed surface of said cover without substantial protrusion but provide gripping means for aiding in the removal of the cover from said open mouth portion.

2. A molded plastic container comprising a relatively flat rectangular hollow main body portion having a relatively smooth unbroken exterior surface free of protrusions and having a plurality of compartments therein and further having an open mouth portion at one end, a cover having a flange-like portion shaped to intimately

interfit with and seal said open mouth portion and having a peripheral edge portion adapted to overlie the peripheral edge of said main body portion encircling said open mouth portion, a strap portion having its opposed ends formed integral with respective portions of said cover and main body portion whereby said cover is relatively undetachable from said main body portion, and the flange-like portion being on the side of the cover requiring the cover to be folded beneath the strap to position the cover in sealing relation to said open mouth portion.

3. A molded plastic container comprising a relatively flat rectangular hollow main body portion having a relatively smooth unbroken exterior surface free of protrusions and having a plurality of compartments therein and further having an open mouth portion at one end, a cover having a flange-like portion shaped to intimately interfit with and seal said open mouth portion, said flange-like portion having on its outer surface a circumferential bead which is adapted to interfit with a groove in the inner surface of said main body portion, said cover further having a peripheral edge portion adapted to overlie the peripheral edge of said main body portion encircling said open mouth portion, a strap portion having its opposed ends formed integral with respective portions of said cover and main body portion whereby said cover is relatively undetachable from said main body portion, the flange-like portion of the cover being on the side thereof requiring the cover to be folded under the strap to locate it in sealing relation to said open mouth portion.

4. A molded plastic container comprising a relatively flat rectangular hollow main body portion having a relatively smooth unbroken exterior surface free of protrusions and having a plurality of compartments therein and further having an open mouth portion at one end, a cover having a flange-like portion shaped to intimately interfit with and seal said open mouth portion, the outer surface of said flange-like portion and adjacent inner surface of the main body portion having closely interfitting irregularities thereon, said cover further having a peripheral edge portion adapted to overlie the peripheral edge of said main body portion encircling said open mouth portion, and a strap portion having its opposed ends formed integral with respective portions of said cover and main body portion whereby said cover is relatively undetachable from said main body portion, the flange-like portion of the cover being so located as to require folding of the cover underneath said strap to interfit with the open mouth portion of the hollow body and the length of said strap being such that it will overlie the exposed surface of said cover without appreciable protrusion when the cover is in sealing relation to said open mouth portion.

5. A molded plastic container comprising a relatively flat rectangular hollow main body portion having a relatively smooth unbroken exterior surface free of protrusions and having a plurality of compartments therein and further having an open mouth portion at one end, a cover having a flange-like portion shaped to intimately interfit with and seal said open mouth portion and having a peripheral edge portion adapted to overlie the peripheral edge of said main body portion encircling said open mouth portion, said flange-like portion having on its outer surface a circumferential bead which is adapted to interfit with a groove in the inner surface of said main body portion, a strap portion having one end formed integral with the peripheral edge of the main body portion encircling said open mouth portion and having its opposed end formed integral with an edge portion of said cover whereby said cover is relatively undetachable from said main body portion, said flange-like portion of the cover being located on the side thereof requiring the cover to be folded under the strap portion in order to position it in said open mouth portion, and the edge por-

tion of the cover having the strap affixed thereto being at a location remote from the terminus of the strap with said body portion when the flange-like portion thereof interfits with the open mouth portion of the hollow body and said strap portion being of a dimension to overlie the exposed surface of said cover without substantial bulging and provide gripping means for aiding in the removal of the cover from said open mouth portion.

6. A container comprising a hollow body having an entrance into the interior thereof and a cover shaped to fit over said entrance and seal the same, said cover being attached to said hollow body by means of a flexible portion formed integrally with said cover and body, said flexible portion being joined to the body to one side of the entrance thereto and further being folded over itself adjacent its joinder with the cover to locate said

cover beneath said flexible portion when the cover is fitted over said entrance, and said flexible portion being so dimensioned that it will bulge over the top surface of the cover only sufficiently to permit it to be conveniently gripped as an aid to removing the cover from its fitted relation over the entrance to the interior of the body and without otherwise forming an interfering protrusion.
